UNITED STATES PATENT OFFICE.

WILLIAM RUMPF, SR., OF SOUTH LANGHORNE, PENNSYLVANIA.

DESIGN FOR A BEDSPREAD.

Application filed November 13, 1924. Serial No. 11,368. Term of patent 7 years.

To all whom it may concern:

Be it known that I, WILLIAM RUMPF, Sr., a citizen of the United States, residing at South Langhorne, in the county of Bucks and State of Pennsylvania, have invented a new, original, and ornamental Design for a Bedspread, of which the following is a specification, reference being had to the accompanying drawing, forming part thereof.

The figure is a face view of a portion of a bed spread showing my new design, that portion of the spread illustrated being repeated in each corner.

What I claim is:

The ornamental design for a bed spread as shown.

WILLIAM RUMPF, Sr.
